COMBINED FLUE AND CHECK DRAFT DAMPER UNIT

Michael A. Crozier, Mount Vernon, N. Y., assignor to National Fuel Conservation Co., Inc., White Plains, N. Y., a corporation of New York

Application July 17, 1952, Serial No. 299,346

18 Claims. (Cl. 126—292)

This invention relates to a control apparatus for improving the thermal functioning of a furnace or boiler wherein the heat of combustion of a fuel is to be transferred to a medium to be heated, such as water, steam, or air, as in a household heating system, and wherein products of combustion or flue gases have to be disposed of as by a chimney or stack.

One of the objects of this invention is to provide a safe, practical, and efficient device or apparatus for improving the transfer of the heat energy of the fuel to the boiler or furnace medium, to make more effective the heat transfer areas or surfaces of the boiler or furnace, and to lessen heat losses to the chimney or stack, all while maintaining proper draft and even though the furnace installation meets with various factors of variability. Another object is to provide a device or apparatus of the just-mentioned character which will be self-adjustable to variations or changes in the pressure of the gases of combustion and constructed and operating so as to require no manual setting or adjustment once it is initially set to function in a given installation.

Another object is to provide a compact unit form of device or apparatus of the above-mentioned character that is of simple, rugged, and durable construction, that can be inexpensively fabricated and assembled, and in which such movable parts as are exposed to the flue gases are movably mounted in a manner to resist such corrosive action of the flue gases as might detrimentally affect long-lasting ease and freedom of movability and gas-pressure responsiveness.

Another object is to provide a simple and compact unit-type of device or apparatus, of the above-mentioned kind, that can be easily and inexpensively installed, particularly in existing installations of boiler or furnace and chimney. Another object is to provide a device of the above-mentioned kind that can be speedily installed and in foolproof manner. Another object is to provide a device of the above character that can be readily associated with the flue or "smoke" pipe that leads from the boiler or furnace to the chimney and, moreover, that is so constructed as to achieve such assembly to the flue and to achieve its intended functioning regardless of any angularity that the axis of the flue might have to the horizontal plane.

Another object is to provide a simple, dependable and foolproof mounting assembly of a device of the above-mentioned character with its mounting or support, such as a flue pipe. More particularly, it is an object of this invention to facilitate the installation of the device or apparatus on or in a flue pipe, to avoid damaging mutilation of the flue pipe where the device is assembled to an existing installation, and to achieve assembly of the device and the flue pipe in a manner that dependably prevents misalignment or other inadvertent derangement as would cause binding or other interference of the flue pipe or parts thereof with moving or movable parts of the device itself. Another object is to pro-

2

vide a device or apparatus of the above-mentioned kind with alining or securing means adapted automatically to coact with easily prepared parts or portions of the flue to facilitate foolproof assembly. Another object is to carry out the just-mentioned object by means that are readily and inexpensively adaptable for coaction with other securing or anchoring means or devices. Another object is to provide, in a device of the above-mentioned character, means for facilitating precision cutting of an opening in the flue pipe and for insuring proper assembly and alinement of the device relative to both the flue and the opening cut into the flue.

Another object is to provide a device of the above-mentioned character with a flue-gas-pressure-responsive damper and with a controllable air-admitting vent to the chimney gases constructed and arranged in a compact unit that is easily installed in an existing flue and that is adjustably associated in the unit in a manner to be readily adjusted or set to meet the widely varying conditions of combustion as well as conditions of installation met with in practice.

Other objects will be in part obvious and will be in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which is shown illustratively a preferred embodiment of my invention and in which similar reference characters refer to similar parts throughout the several views of the drawings,

Figure 1 is a top elevation of a flue showing how it is prepared for installation of my device;

Figure 2 is a side elevation thereof as seen from the bottom of Figure 1;

Figure 3 is a top elevation of the device of my invention, with a vent control part removed, showing the device in substantial readiness to be assembled to the flue of Figure 1;

Figure 4 is an elevation as seen from the bottom in Figure 3, showing the device, also with the vent control part removed, in relation to the flue of Figure 2 and in substantial readiness to be assembled thereto;

Figure 5 is an end elevation as seen along the line 5—5 of Figure 3, showing the device in process of assembly to the flue;

Figure 6 is a view like that of Figure 5, showing completion of the assembly of the device to the flue, with the air-vent control part omitted;

Figure 7 is a central vertical sectional view as seen along the line 7—7 of Figure 6;

Figure 8 is a side elevation as seen from the right in Figure 6, showing the completed assembly of the device to the flue, with the air-vent control part in position;

Figure 9 is a transverse sectional view as seen along the line 9—9 of Figure 8;

Figure 10 is a fragmentary elevation, on a larger scale, showing a bearing assembly and shaft mounting;

Figure 11 is a side elevation like that of Figure 8, showing the complete device assembled to a flue with modified forms of locating and securing means;

Figures 12 and 13 are fragmentary vertical sectional views as seen along the lines 12—12 and 13—13, respectively, of Figure 11, and

Figure 14 is a plan view of a template, on a much reduced scale, showing, in development, the shape and relative locations of cutouts to be made in the flue.

In the illustrative and preferred embodiment of my invention the device, comprising a unitary assembly of a biased pressure-responsive damper and a controllably vari-

able air-vent for checking chimney draft, is to be installed at about the point where the gases of combustion leave the boiler or furnace, whence they are conducted by a flue to the chimney; a convenient and preferred assemblage of my device at that location comprises interrelating my device directly to the flue, preferably in close proximity to the furnace end of the flue, and in Figures 1 and 2, there is shown at 20 a section of such a flue which, for convenience of description, has its axis horizontal, though—as is later pointed out—the device may be assembled to, and set for functioning with, a flue whose axis is vertical or at any angle between the horizontal and the vertical. The arrows in the drawings indicate the direction of travel of the gases of combustion so that in Figures 1 and 2 the left hand end of the flue is the furnace end and the right-hand end leads to the chimney or stack. The biased damper of the device has to be gotten into the inside of the flue 20 and, for air-admission for draft checking the flue 20 has to be provided with an air-vent or opening, while, on the other hand, the sequential relation of damper and air-inlet has to be properly oriented with respect to the direction of flow of the gases of combustion. Moreover, damaging or weakening mutilation of the flue pipe, usually of sheet metal, should be avoided. One of the dominant aims of this invention is to provide a construction by which facile and proper installation of the device may be dependably effected.

In the drawings I have shown the flue 20 as of circular cross section, that being in wide and common use, and for that shape of flue the saddle-like frame 21 (Figures 3, 4, 5 and 6) is shaped concave on its under side of the same radius as that of the flue to interfit with the latter when set transversely thereon, being of an overall extent about equal to half of the periphery of the flue, illustratively (see Figure 6) being of about 180° in extent. The frame 21 is devised to be in a form that can be easily cast, as of cast iron, and it comprises a central or middle portion 22 that is of relatively small dimension lengthwise of its axis of curvature, being, however, of substantial thickness or dimension in radial direction (see Figures 5 and 6), so that it has substantial strength and rigidity; its under face is, as above noted, concave, to match the curvature of the flue 20, and preferably its upper face is also arcuate, being convex to give it the desired radial thickness and also, when seated against the flue 20 as in Figure 6, to cause it as a whole to rather closely hug the flue and to avoid ungainly and wasteful projecting parts. With such conformation it is like a strong arcuate rib external of the flue 20, is neat in appearance, and not wasteful in material. In the illustrative embodiment it subtends an angle of about 90° or so.

At its ends and integrally formed or cast therewith the central frame portion 22 has arcuate plate-like depending and offset extensions 23, 24, being offset to the left as viewed in Figures 3 and 4; they are internally concave and of the same radius of curvature as the under face of the central portion 22, and they can be thinner than the latter, as shown in Figure 5, their external faces being appropriately convex for substantial uniformity of thickness throughout. As viewed in Figures 5 and 6, the frame portions 23, 22, 24, together subtend an angle of about 180°, thus enveloping half of the periphery of the flue when seated transversely thereon as in Fig. 6.

The upper ends of the plate-like extensions 23, 24 are provided with upstanding substantially parallel ribs 25, 26 respectively (Figures 3, 4 and 5), and their top edges as viewed in Figures 5 and 6 terminate in a curved plane which coincides with the surface of revolution of the upper face of the central frame portion 22, and the external sides or faces of the ribs 25, 26 bulge outwardly, as is better shown in Figures 5 and 6, forming external shallow grooves or guideways which are parallel to each other and parallel to the axis of the flue 20 when the frame is seated against the latter. These ribs 25, 26 serve, at their top edge faces, as spaced parallel seats for a

cover-plate 27, shown in Figures 8 and 9, means being provided for adjustably setting the cover-plate 27 for air-inlet control, as is later described. The plate 27 is arcuate, its external surface having a radius of curvature the same as that of the top face of the central frame portion 22 (see Figure 8), but preferably the plate 27 is thinner than the frame portion 22, having an inner face of larger radius of curvature than the external radius of the flue 20, so that when its ends rest on the ribs 25, 26 plate 27 is held spaced from the flue 20. Externally the plate 27 appears almost like a frame part companion to the central frame portion 22 even though broader than the latter (see Figure 8), and at its arcuate end remote from the central frame portion 22 plate 27 has an inwardly extending flange 28 which seats against the flue 20, having a similar radius of curvature, and it can coact in the mounting of frame 21 onto the flue.

At its respective side ends, as seen in Figure 9, the cover-plate 27 terminates in parallel flanges 30, 31, which 20 overlie the external side faces of the parallel flanges 25, 26 respectively, coact with the latter in slidably guiding the cover-plate lengthwise of the flanges 25, 26, and in directions toward or away from the central frame portion 22, as seen in Figure 8, so as to vary at will the size of the gap, indicated at 32, therebetween, for purposes later described. Means are provided for fixing the cover-plate in its selected position, and such means may comprise screws 33 (Figures 8 and 9) threaded into the flanges 30, 31 so that their free ends can engage against the flanges 25, 26, preferably in the longitudinal external grooves in the flanges 25, 26, and in this manner the cover-plate 27 may be clamped and held in its selected position. In the illustrative embodiment two such screws 33 are shown, one at each side flange of the closure plate 27, being preferably located, as is better shown in Figure 8, at the lefthand ends of the flanges 30, 31, both of which may be extended toward the left for that purpose; as shown. Preferably, the screw ends abut against the downwardly and inwardly inclined side faces of flanges 25, 26 so that the clamping pressures exerted by the screws are resolved also into downward components, thus also drawing the plate 27 downwardly, as viewed in Figures 8 and 9, to seat it well against the tops of the flanges 25, 26 and also to seat the cover-plate flange 28 against the flue 20.

The offset depending side portions 23, 24 of the frame, as viewed in Figures 7 and 8, are provided with bearing means for pivotally supporting a damper 35 which, where the flue is of circular cross section, is also, and preferably, circular or disk-like, but of diameter materially less than the inside diameter of the flue, somewhat as indicated in Figures 6 and 9, in order to leave substantial passageway for gases of combustion even when the damper stands at right angles to the axis of the flue. The damper 35 is provided with shaft means for coaction with the bearings in the frame 21 and, conveniently, the damper 35 and its shaft means may be cast integrally or in one piece with the axially aligned pivoting shafts 36, 37 projecting from opposite sides of the periphery of the damper; in the embodiment shown the pivot shafts 36, 37 are aligned on a chord parallel to and above the horizontal diameter of the damper (Figures 6 and 9) in order that the damper be responsive to and tiltable by the pressure of the gases of combustion emitted by the furnace. One of the pivot shafts, 37, is longer than the other one, 36, and the frame portions 23, 24 are provided with round holes 38, 39, which are preferably considerably larger than the diameter of the pivot shafts of the damper, and they may be formed by drilling or in the course of casting of the frame 21. Preferably, each is provided with a bearing which may be in the form of a bushing, conveniently in the form of an eyelet of relatively large diameter, which is simply set into the frame hole and its unflanged end thereupon expanded or spun over to hold it in place. In Figure 9 these eyelet bearings are shown at 40, 41, and in Figure 10 one of

them, namely, eyelet bearing 41, is shown on a larger scale to better indicate the coacting relationships. Preferably and conveniently, each eyelet bushing is relatively loosely mounted in its frame-hole, and it can be free to partake of rotary movement relative to its supporting frame part. Though the two depending frame parts 23, 24 (Figure 9) need not be geometrically parallel nor need the bearing holes 38, 39 therein be axially alined, the relative looseness of fit of the eyelet bearings gives the latter some leeway to more closely approximate coaxiality, and the loose fit of the pivot shafts 36, 37 in the eyelet bearings in turn makes it unnecessary for high precision of bearing alinement.

Moreover, as the damper 35 and its pivot shafts oscillate, in use, relative rotary movement can take place between each pivot shaft and its eyelet bearing and also between the eyelet bearing and the frame hole in which it is loosely mounted. These coactions make for greater ease of pivoting movement or oscillation of the damper and coact to prevent sticking or "freezing" by foreign material. For example, such relative rotary movements tend always to shift, relatively, engaging bearing or contact surfaces, having, in effect, a self-cleaning action, while the axial tilt of the surface of the frame hole and of the surfaces of the loosely mounted eyelet bearing, in relation to the axis of the pivot shaft, tends to effect discharge from these surfaces of such foreign matters as might tend to accumulate on them but are continuously loosened and shifted by the relative rotary movements of these parts.

The damper 35 is assembled to the frame 21 by first inserting the long pivot shaft 37 through frame hole 39 from the inside of the frame, whence the short pivot shaft 36, by appropriate tilting of the damper unit, an action aided by the above described looseness of the bearing mounting, is brought to the inside end of the eyelet bearing 40 and entered in to the latter to the extent permitted by stop flanges 42 (Figure 9) formed integrally with and in the plane of the damper 35 itself. The other pivot shaft 37 is provided with a hole 43 (Figure 10), through which is then passed a cotter pin 44 (see also Figure 7) with the plane of its eye transverse of the shaft axis and with its ends wrapped in opposite directions about the shaft, as shown in Figure 7, so that it serves in effect like a peripheral shoulder or ring to coact with the inner flange of the eyelet bearing 41 to hold the damper unit 35 against shift to the right as viewed in Figure 9. The cotter pin 44 at one end and the stop flanges 42, 42 at the other end thus, in effect—though somewhat loosely—hold the center of the damper in coincidence with the vertical center line of the frame and of the flue, holding the damper against material shift in the direction of its axis.

As viewed in Figures 9 and 6, the area of the damper below the pivoting axis is greater than the area above the axis, that being achieved, in the illustrated embodiment, by having the pivoting axis displaced from and parallel to a diameter of the damper; the damper accordingly is shiftable about its axis in response to the pressure of the moving gases of combustion when the unit is related, as later described, to a furnace or its flue, and though a substantial flow passage, annular in shape, exists between the damper periphery and the flue when the damper stands transversely of the flue, it is desirable to make provision for increasing the area of that flow passage by causing the damper to tend to assume a position that is at an angle to a plane transverse of the flue, thus decreasing the effective size of the flow passage between the damper and the flue; I make such provision by adjustably biasing the damper 35 out of its tendency to assume a true vertical position, preferably by means of a weighted lever 46 adjustably attached to the outer projecting portion of the pivot shaft 37 (Figures 9, 6 and 4).

Weighted lever 46 is conveniently in the form of a casting, provided with a hub 47 that has a round hole

therein so that it can be easily slid onto the round shaft 37, and spaced from the hub 47, and preferably outwardly offset therefrom (Figures 9 and 6), is the weighted portion 48 of the lever, conveniently cast in the form of a disk of appropriate diameter and thickness, joined to the hub by a thinner web-like portion 50. Suitable means are provided to lock the hub 47 to the shaft 37 in the desired relation of angularity of the weighted lever 46 to the damper 35, and such means conveniently comprises a setscrew 51 (Figures 9, 4 and 3).

The shaft 37 projects beyond the hub 47, and that projecting portion is shaped as indicated at 52, as by flattening two opposed sides thereof to form an acute angle (Figure 4) that simulates an arrowhead pointing in the line or plane of the damper 35 and pointing toward that side of the pivoting axis on which extends the smaller area of the damper. The indicator part 52 of shaft 37 thus always gives a visual indication of the rotary position of the damper even though the damper becomes fully enclosed within the flue, as is later described. As is better shown in Figure 4, suitable indicia, such as the therein-indicated numbers "1," "2" and "3" may be provided on the outer end faces of the hub 47 to aid in setting the weighted lever 46 in relation to the arrowhead indicator part 52 and, hence, in relation to the plane of the damper 35 itself. Moreover, as better appears from Figures 6 and 9, the offset shaping of the weighted lever 46 insures that it is always assembled to the shaft 37 with the numbered hub face at the outside of the assembly; as is later explained, the lever 46 is given its desired setting after the device is installed and related to the flue 20, and even if the lever 46 were to be removed from shaft 37 during such adjustment it cannot be reassembled thereto in reversed relation, for the offset weighted portion 48 would collide with the flue or other parts and the hub is thus prevented from being slid onto the round portion of shaft 37.

The resultant unit, including securing and alining means later described, is compact, easily fabricated and assembled, with a minimum of machine tool operations; and its parts are so devised and so capable of assembly that very substantial dimensional tolerances are permissible, even such as include normal tolerances that accompany quantity production of parts, as by molding and casting. As above indicated, the frame 21, the closure plate 27, the damper 35 with its pivoting shafts 36, 37, and the weighted lever arm 46, can be individual castings of cast iron; the arrowhead indicator 52 on shaft 37 and the indicia on the lever hub 47 can all be cast. The eyelet bearings 40, 41 can be of relatively light sheet brass, and as above described, they fit loosely in their respective frame holes and, in turn, the pivoting shafts 36, 37 fit loosely into them, not only speeding and facilitating assembly but also achieving great ease and sensitiveness of pivoting movements of the damper 35 accompanied by self-cleaning relative rotational movements, movements which also coact, in effecting bit by bit turning of the loose eyelet bearings themselves, to repeatedly change or shift points or surfaces of bearing contacts. Moreover, these features of the multiple bearing structures are of long-lasting action and are well adapted to meet the widely changing temperature conditions of operation of the device.

In Figures 1 and 2 are shown how I prepare the flue 20 for the reception of my device. At the selected point, preferably closely adjacent the furnace, which is assumed to be at the left hand end of the flues shown in these two figures, I cut the sheet metal of the flue for the entry into it of the damper 35 and for quickly and dependably locating and securing my device in position. Transversely of the flue 20 I cut an opening, generally indicated by the reference character 55, the opening being relatively narrow and of a peripheral extent less than the peripheral extent of frame 21 but somewhat greater than the peripheral extent imposed by the above de-

scribed multiple bearings in the frame for the damper shafts, and geometrically positioned in relation to the cutout opening 55 I provide an additional cutout, preferably in the form of two round holes 56, 57, which can conveniently be made by drilling. The cutout opening 55 has a central or middle portion 58, which is bounded by two parallel arcs 61, 62, which are of an extent at least equal to the arcuate spacing of the upstanding flanges 25, 26 of the saddle-like frame 21 of the device, and at the side ends of this middle opening portion 58 the cutout is extended into symmetrical narrower portions 63, 64, which are offset and inclined toward the furnace end of the flue 20, as is clearly shown in Figures 1 and 2. Each of these extensions or end portions 63, 64, also are preferably tapered as shown, terminating in rounded ends of a radius materially greater than the radius of the bearing mountings for the damper shafts, and the drill holes 56, 57 are located in alignment on a chord of the flue 20 and just below and toward the chimney sides of the offset end portion 63, 64 of the cutouts, being accurately located in relation to the centers of the radii of the rounded ends of these cutout end portions of the opening.

To facilitate so preparing the flue 20, I provide a template 66 shown on a smaller scale in Figure 14; it can be made of paper and has printed on it, as at 67, a development of the above described cutout 55, and also the center locations, as by the cross marks 68, 69, of the holes 56, 57 to be drilled in the flue 20. Printed on it can also be suitable legends of instructions as suggested in Figure 14.

Such a template 66, after cutting out the area within the line of development 67, is then fastened, as by adhesive tape, transversely of the selected portion of the smoke pipe or flue 20, with the line along which the arc 61 (Figures 1 and 2) is to be cut positioned on the furnace side of the flue location, according to the printed legends of instruction. With the template so secured the outline of the development 67 on the template is easily marked or scored on the sheet metal, and the two holes 56, 57 easily drilled and accurately located relative to each other and to the scored outline for the opening 55, whereupon the sheet metal is cut along those scorelines and the cutout 55, as described above, formed.

The unit device, for purposes of assembly to the flue 20, may or may not have the closure element or plate 27 removed therefrom, but for purposes of better illustration of the manner of assembly the closure element 27 is omitted in the views of the device as shown in Figures 3, 4, 5 and 6; it has, moreover, suitable elements for coaction with the drilled holes 56, 57 of the flue, and in one form of construction these elements comprise the heads 72, 73 of bolts 74, 75 respectively, which pass through suitable holes respectively provided in the depending offset side portions 23, 24 of the saddle-like frame 21 and fixed in position by their respective clamping nuts as shown, with the heads 72, 73 projecting from the inside concave face of the frame which is to interfit with the convexity of the flue 20; these holes locate the boltheads 72, 73 in the same geometrical relation to the pivoting axis of the damper 35 as the template 66 locates the holes 56, 57 in the flue in relation to the centers of the radii of curvature of the offset end portions 63, 64 of the cutout opening in the flue; the boltheads 72, 73 are preferably of substantial size, being preferably cylindrical in external contour and the holes 56, 57 in the flue are drilled to a size or diameter that will just neatly receive the boltheads therein.

The bolts 74, 75, in this embodiment, are used to clamp against the outer curved faces of the frame parts 23, 24 two heavy sheet metal straps 77, 78 (Figures 5 and 6) which have their anchored ends apertured so they can be slipped over the outer ends of the bolts and clamped as aforesaid by the respective nuts of the latter (Figures 3, 4 and 5) and ultimately can extend about the rest

of the periphery of the flue, their free ends being bent and apertured, as shown, to receive a clamping bolt 80 (Figure 6).

The inwardly projecting boltheads 72, 73, thus made unitary with the side frame parts 23, 24, and the frame 21 form an integral whole that may now be applied to the flue and as a unit coact with the deformable flue in achieving assembly to the latter, as in the illustrative manner about to be described.

In attaching the device to the flue the bolt 80 is removed and the straps spread apart to straddle the flue as the device, held transversely of the flue and with the lower end of the damper 35 entered into the cutout opening 55, is let down onto the flue. As it is moved downwardly in Figures 2 and 5, the laterally projecting portions of the damper 35 including the pivoting shafts 36, 37 enter the cutout extensions 63, 64 and the upwardly exposed downwardly inclined edges of the latter impose a guiding shift upon the entire unit toward the left in Figures 1 and 2 as the concave underface of the frame 21 approaches the convex surface of the flue, thereby shifting the projecting parts 72, 73 toward holes 57, 56. The projecting boltheads 72, 73, slide along the exterior of the flue, which is now purposely deformed to enter into the holes. For example, by pressing downwardly on the unit, boltheads 72, 73 press opposite sides of the flue (see Figure 5) toward each other; the circular flue cross section is distorted into a sort of oval shape (shown in somewhat exaggerated form in Figure 5) to register head 72 with hole 57 and head 73 with hole 56. Or, one head may first be entered into its flue hole and the other used to press the sheet metal flue side inwardly by downward pressure on the frame to enter it into its hole.

By such movements, aided by easily effected manual shifting and adjusting of the unit relative to the flue, the boltheads 72, 73 are maneuvered simultaneously or successively into registry with the holes 56, 57; in either case, due to the resiliency or spring-back of the sheet metal of the flue, the inwardly pressed side or sides of the flue in effect snap outwardly when registry is achieved and thus the boltheads are also dependably held in their respective holes.

The resultant relationship of the parts is shown in Figure 6. The bearing structures are centered to the cutout extensions 63, 64 and the damper 35 becomes concentrically positioned within the inside periphery of the flue 20, insuring uniform width of the annular free passageway which is intended to be provided by the smaller diameter of the damper 35. Such interengagement of these projecting parts with the holes in the flue achieve a quite dependable attachment of the unit to the flue, in that the unit device cannot be shifted or removed without forcibly disengaging the inwardly projecting parts from their respective holes in the flue. It is preferred, however, to provide additional security of attachment so as to guard against the chance that the person installing the device might drill the holes to materially greater size than is appropriate for ease of interengagement in the manner earlier above described, and to that end the clamping band members 77, 78 may be employed, being extended the rest of the way around the periphery of the flue and put under tension by the bolt 80, as in Figure 6. With the anchored ends of the straps 77, 78 attached against the outer faces of the offset frame parts 23, 24 respectively, the major engagement of the clamping straps with the flue 20 is along a substantial peripheral portion at the bottom of the flue, as better appears in Figure 6, with the result that the clamping action is upwardly in the direction of the vertical diameter of the flue and acts not only to tightly seat the upper reach (of about 180°) against the mating concave under face of the saddle frame 21, but also tends to strain the two opposed sides of the flue outwardly away from each other and thus insure against any receding movement of the sheet metal

of the flue in directions to disengage either of the projecting bolthead 72, 73.

Such clamping action also reinforces and strengthens the flue throughout the region where it is cut out, and in this coaction the closure part 27, as is better seen in Figure 8, can also take part in that, whatever position it is given lengthwise of the parallel frame flanges 25, 26, its clamping screws 33, 33 act to draw it and its flue-engaging flange 28 downwardly; with the flange 28 thus snugly and tightly seated against the flue on the furnace 10 side of the cutout 55, and with the arcuate metal portion 22 of the frame seated on the chimney side of the cutout 55, the above described reinforcing action on the flue becomes well distributed about the flue relative to the cutout area thereof.

Other means for supplementing the securing action of the frame-projecting parts and the holes in the flue may be provided, such as shown in Figures 11, 12 and 13, where, instead of providing the clamping straps 77, 78 as above described, I provide other means for holding the sheet metal of the flue from being pressed or distorted in directions to effect disengagement of a projecting part of the frame from the whole in the flue, and such means may comprise a hole 82 in each of the depending offset side portions 23, 24 of the saddle-like frame 21, located closely adjacent the inwardly projecting part on each of these frame portions 23, 24, conveniently at points, as is indicated in Figure 11, just about midway between the location of the inwardly projecting frame part and the location of the bearing means in the frame. Through such a hole, after drilling a smaller hole 83 (Figure 12) in the sheet metal of the flue 20, is then driven a screw 84 of the so-called "sheet metal" type adapted, as is well known, to thread itself tightly into the sheet metal, thus clamping each of the two opposite sides of the flue tightly against the inner faces of the offset frame portions 23, 24. With such a coacting anchorage of the sheet metal of the flue, the inwardly projecting parts of the frame need not take the form of bolthead like those of the bolts 74, 75 above described in connection with Figures 5 and 6, but may take any other suitable form, such as projections as shown at 85 in Figure 13 and also indicated in Figure 11, cast integrally.

The coacting locating and securing parts, meaning the inwardly projecting parts on the frame and the holes in the flue, coact to achieve other advantages; their respective relationships to the bearings and pivoting shafts of the damper 35 and to the rounded ends of the cutout extensions 63, 64 (Figures 1 and 2) are such that it is impossible to bring about a binding action or other interference between the pivoting shafts of the damper, including the eyelet bearings, with the sheet metal of the flue, the coacting parts acting so to position these parts in relation to one another that there is always substantial and, in fact, symmetrical or balanced clearance; once these projecting parts and their flue holes are interengaged it is impossible for the workman to effect any such shift of the unit device relative to the flue as would disturb such clearances or as would achieve any other misalignment. For example, relative rotative displacement between the unit device and the flue is also dependably prevented, and thereby the opening in the saddle-like frame part 21 that is bounded by the parallel flanges 25, 26 and the arcuate middle frame portion is properly located over the middle portion 58 (Figure 1) of the flue cutout 55, and the offset side portions 25, 26 of the frame are dependably located in position to cover over the offset cut out extensions 63, 64 respectively. Moreover, it is as good as impossible to assemble the unit device to the flue with the device reversed end for end in relation to the axis of the flue; for example, suppose that the device as shown in Figure 4 were first turned through 180° and then it was sought to let it down onto the flue 20 of Figure 2, with the damper and its shafts entering the cutout. In such case the two inwardly projecting frame

parts such as the bolthead 72, 73 of Figure 5, or the parts 85 of Figures 11 and 13, would fall in a vertical plane to the left of the downward and leftward inclined cutout extensions 63, 64 and engage side portions of the flue where there are no holes or cutouts to receive them, tending to press the flue sides inwardly and to distort the flue into a curvature with which the under side of the saddle-like frame 21 could not and would not mate; accordingly, seating of the frame in position is precluded.

With installation completed, the full unobstructed area of the middle portion 58 of the cutout, bounded by the parallel transverse arcs 61, 62 in Figures 1 and 2, and bounded at its ends by the parallel frame flanges 25, 26, is available for dependable control of entry of air from the atmosphere into the flue, by properly setting closure plate 27 lengthwise of the frame flanges 25, 26 and, as is better shown in Figure 8, toward or away from the arcuate middle frame portion 22. All that need be done is to loosen up the screws 33, 33, set the plate 27 in the desired position to give the desired vent opening at 32 in Figure 8, and tighten up the screws. The setting of the slide plate 27 may vary from a position of maximum opening for maximum inflow of air to substantially zero opening, depending upon the characteristics of the furnace or boiler and chimney installation. This setting is made after first setting and locking the weighted lever 46 in relation to the pressure-responsive damper 35. Here it is sought and desirable to set the weighted lever at such an angle to the arrowhead indicator 52 (Figure 4) on the damper shaft that the damper 35 is in "closed" position, meaning a position of minimum opening for normal furnace operation. This damper 35 may be in a plane about transverse to the axis of the flue, but usually at a small angle of tilt in opening direction as indicated in Figure 8, taking into consideration the normal pressure of the flowing gases of combustion tending to swing it in opening direction against the action of the weighted lever arm 46. The continued flow of gases of combustion to the chimney proceeds by way of the annular flow passage between the periphery of the damper and the inside periphery of the flue (see Figure 9). The resultant opposition to high velocity escape from the furnace of the hot gases of combustion in effect backs them up somewhat within the furnace or boiler, causing them to churn more rapidly and hold and bring them into contact with heat transfer surfaces for longer time intervals and for efficient loss of heat therefrom to the medium which is to be heated by the furnace, accompanied by a more thorough scrubbing action on the furnace or boiler heat transfer areas. The device is particularly effective with furnaces or boilers equipped with oil burners. Gases of combustion can escape to the chimney through the above-mentioned annular flow passage about the periphery of the damper 35; they can pass through that passage at high velocity, but their movement within the boiler or furnace and up to the damper is slowed up to give better heat transfer as above mentioned but also more thorough combustion, causing also substantial increase in the temperature within the combustion area. As a result, heat absorption or transfer to the medium to be heated within the boiler or furnace is of materially greater efficiency, and loss of heat to the stack or chimney can be very substantially reduced.

Furthermore, the mechanism is sensitively responsive to changes in the pressure of the gases of combustion leaving the boiler or furnace; sudden increases in the pressure immediately act upon the damper 35 to tilt it further in opening direction against the action of the weighted lever arm 46, and thus such pressures are quickly relieved. The sensitiveness of pivoted mounting of the damper 35 and the above described coactions of the bearing constructions can coact toward long-lasting pressure-responsive sensitivity.

In the drawings, the device is shown, for purposes of greater ease of understanding, as applied to a horizontal

flue or smoke pipe, but as above noted the device is attachable to and adjustable to coact with a flue of any angularity including a vertical flue, so long as the axis of the damper is horizontal. All that need be done for any angle of the axis of the flue is simply to loosen up the setscrew 51 on the hub of the weighted lever 46 and, for any given or normal operating pressure of escaping gases of combustion, shift the weighted lever about the axis of its supporting shaft 37 to, and secure it in, that position in which the torque it exerts in closing direction on the damper 35 opposes the torque exerted in opening direction on the damper by the pressure of the gases of combustion with the damper in as near to transverse or "closed" position as possible or as operating conditions dictate. The arrowhead 52 on damper shaft 37 always gives an external visual indication of the plane of the damper relative to the longitudinal axis of the flue, whatever the angularity of the flue itself.

And for any such setting of the damper and weighted lever, the closure plate 27 is set for appropriate ingress of air to the flue on the chimney side of the damper for checking draft according to whatever are the characteristics (furnace, flue, chimney, etc.) of any particular installation; such setting of the closure plate 27 may be, as above noted, from a maximum air-inlet opening to zero and in the latter case the cutout opening in the flue is completely covered over and substantially closed off.

It will thus be seen that there has been provided in this invention a device in which the various objects above set forth, together with thoroughly practical advantages, are successfully achieved.

I claim:

1. A regulator installation comprising a regulator and a sheet metal flue for conducting gases of combustion from a furnace or the like to a chimney, said flue having a cut-out opening of an overall extent about half way about the periphery of the flue and being of relatively small dimension lengthwise of the flue, said opening having a middle portion that is substantially parallel-sided with narrower end portions that are offset toward the flue-gas entry end of the flue, said end being adapted to be connected to the furnace, the sheet metal of the flue having two small apertures on opposite sides thereof respectively adjacent said end portions of said cut-out opening and substantially alined on an axis that passes transversely through the flue, said regulator comprising a saddle-like frame whose under side substantially mates with the transverse contour of the flue substantially throughout the peripheral extent of said cut-out opening, said frame having a middle portion provided with an opening to overlie said middle portion of said flue opening and depending side portions to cover over the respective narrower offset end portions of said flue opening, said frame side portions being provided with alined bearing means, a damper having shaft means pivotally supported in said alined bearing means whereby, as said frame is set transversely onto said flue, said damper enters through the cut-out opening in the flue and the damper shaft means are guided by the respective offset end portions of said flue opening to occupy positions respectively adjacent the extreme ends thereof, thereby positioning the damper axis on the side of said opening that is toward said flue-gas entry end of the flue, said depending side portions having inwardly projecting juxtaposed alined projections which press opposed sides of the sheet metal flue toward one another as said frame is set onto the flue to respectively enter said opposed apertures upon spring-back of said flue sides when respectively alined therewith and thereby locate and hold said frame and damper against shift relative to the flue and its cut-out opening and to position the frame so that said opposed shaft means of the damper are out of contact with the sheet metal at said offset ends of said cut-out opening, said damper having a greater area on that side of its axis of pivoting that is remote from said

cut-out opening whereby increase in pressure of the gases of combustion is effective to tilt the damper in a direction to move the damper portion on the other side of said axis in a direction toward said flue-gas entry end and away from said cut-out opening, and cover means movably associated with said frame and the opening therein for determining at will the effective area of the opening for ingress of air into the flue on the flue gas exit side of said damper.

2. A regulator installation comprising a sheet metal flue of circular cross section for conducting gases of combustion from a furnace or the like to a chimney, said flue having a transverse cut-out opening of an arcuate extent on the order of 180° and of relatively small dimension lengthwise of the flue, said opening having a middle air-entry portion that is bounded by two arcs spaced lengthwise of the flue and narrower end portions that are inclined and offset beyond that arc that is nearer the flue-gas entry end of the flue, said end being adapted to be connected to the furnace, said regulator comprising a rigid saddle-like frame which on its under side has a radius of curvature equal to that of said flue for external seating engagement with the flue, said frame comprising a middle arcuate narrow portion adapted to seat against the flue adjacent that boundary arc that is nearer the flue-gas exit end of the flue that is adapted to be connected to the chimney and terminating in depending offset side portions to cover over the respective offset end portions of said cut-out opening in the flue, said side portions being provided with alined bearing means carrying a damper of lesser diameter than the inside diameter of the flue, said damper having shaft means pivotally supported in said alined bearing and extending along a chord above the diameter of the damper whereby, as said frame is set transversely onto said flue, the damper enters through the cut-out opening in the flue and the damper shaft means are guided respectively by said inclined offset end portions of said opening to shift the frame toward said flue-gas entry end and position the damper axis on that side of the air-entry portion of said flue opening that is toward said flue-gas entry end and position said arcuate middle portion of the frame against the flue on the side of said flue opening that is toward said flue-gas exit end, one of said shaft means projecting beyond its associated depending side portion of the frame and having secured therat a weighted lever arm that biases the damper to swing its lower part in the direction of flow from said flue-gas entry end to said exit end, an arcuate cover-plate overlying said air-entry portion of the cut-out flue opening and having an arcuate portion seating against the flue on the side of said cut-out opening that is toward said flue-gas entry end, and means securing said arcuate cover-plate for adjustable movement in directions toward or away from said narrow middle portion of the frame to vary the size of the effective aperture therebetween for ingress of air.
3. A regulator installation as claimed in claim 2, in which the last-mentioned means comprise guideways on said depending side portions of the frame for coaction with the respective terminal ends of said arcuate cover-plate whereby said cover-plate may be shifted relative to the frame in a direction lengthwise of the flue, with means for holding the cover-plate in selected position relative to the frame.
4. A regulator installation comprising a sheet metal flue of circular cross section for conducting gases of combustion from a furnace or the like to a chimney, said flue having a transverse cutout opening of an arcuate extent on the order of 180°, said opening having a middle air-entry portion that is bounded by two arcs spaced lengthwise of the flue and end portions that are inclined and offset beyond the plane of that arc that is nearer the flue-gas entry end of the flue, said end being adapted to be connected to the furnace, said regulator comprising a

saddle-like frame which on its under side has a radius of curvature equal to that of said flue for external seating engagement with the flue, said frame comprising a middle portion that is arcuate and relatively narrow adapted to seat against the flue adjacent that boundary arc that is nearer the flue-gas exit end of the flue that is adapted to be connected to the chimney and terminating in depending offset side portions to cover over the respective offset end portions of the cutout opening in the flue, said side portions having bearing means, a damper of lesser diameter than the inside diameter of the flue and provided with shaft means whose axis extends along a chord above the diameter of the damper and whose ends are supported in said bearing means whereby, as said frame is set transversely onto said flue, the damper enters through the cutout opening in the flue and the damper shaft means enter the respective inclined offset end portions of said opening accompanied by shift of the frame toward said flue-gas entry end to position the damper axis on that side of the air-entry portion of said flue opening that is toward said flue-gas entry end and position said arcuate middle portion of the frame against the flue on that side of said flue opening that is toward said flue-gas exit end; said frame and said flue having coacting locating means that are interengaged upon completion of setting the frame onto the flue as aforesaid for fixing the position of the frame against shift about the axis of the flue and lengthwise of the flue and against movement in a direction to unseat it from the flue, and a cover-plate overlying said air-entry portion of the cutout flue opening and having means mounting it in adjustable position relative thereto to vary the size of the effective aperture for ingress of air into the flue.

5. A regulator installation as claimed in claim 4, in which said coacting locating means comprise two holes in the flue respectively underlying said depending side portions of the frame and the heads of two bolts that extend through said depending side portions with the heads projecting inwardly therefrom and respectively received in said holes, the outer ends of said bolts securing the respective ends of strap means that extend about the rest of the periphery of the flue and with said frame, complete the encirclement of said flue.

6. A regulator installation as claimed in claim 4, in which said coacting locating means comprise two holes in the flue respectively underlying said depending side portions of the frame and two inward projections respectively carried by said depending side frame portions and respectively entered into said flue holes.

7. A regulator installation as claimed in claim 6, in which said depending side frame portions and portions of the flue respectively underlying said side frame portions are provided with screw means respectively threaded into said underlying flue portions for holding the latter against inward distortion to thereby prevent disengagement between a flue hole and the projecting part entered into it.

8. A regulator installation as claimed in claim 4, in which said coacting locating means comprises means projecting inwardly from said under side of said saddle-like frame and cutout means in the sheet metal of the flue into which the projecting means is engaged by springback of the sheet metal of the flue following inward distortion thereof as said saddle-like frame is set onto the flue.

9. A regulator for assembly to a sheet metal flue that is of round cross-section and recoverably deformable into substantially oval shape, said flue having a transverse arcuate cutout opening therein and two spaced cutouts adjacent the respective ends of said opening whereby they subtend a substantial angle, said regulator comprising a saddle-like frame which is concave on its under side for external seating engagement with the flue, said frame comprising a middle portion and terminating in depending side portions, said side portions having bearing means, a damper of lesser diameter than the inside diameter of the flue and provided with shaft means and

5 whose ends project beyond the periphery of the damper and are supported in said bearing means whereby the damper enters through said cutout opening in the flue and said ends of the damper shaft means enter the respective end portions of said opening, said frame having integral means, one for each of its depending side portions, projecting substantially radially inward from the curved plane of the under side thereof and subtending an angle substantially the same as the angle subtended by said spaced cutouts in the flue to thereby resist seating engagement of the frame with the flue except under forced seating movement to cause inward deformation at the sides of the flue sheet metal and condition the latter for springback to interengage with the projecting means upon the projecting means reaching respectively said spaced cutouts of the flue as seating movement of the frame continues, thereby fixing the position of the frame against shift about the axis of the flue and lengthwise of the flue and against movement in a direction to unseat it from the flue.

10. A regulator for assembly to a sheet metal flue having a transverse arcuate cutout opening therein and two spaced cutouts adjacent the respective ends of said opening whereby they subtend a substantial angle, said regulator comprising a saddle-like frame which is concave on its under side for external seating engagement with the flue, said frame comprising a middle portion that is cut out, for passage of air, where it overlies the middle portion of said cutout opening of the flue and having bearing means in its depending side portions, said side portions each having integral means projecting substantially radially inward from the curved plane of the underside thereof, said projecting means subtending an angle substantially the same as the angle subtended by said spaced cutouts in the flue, a damper of lesser diameter than the inside diameter of the flue and provided with shaft means whose axis extends along a chord above the horizontal diameter of the damper and whose ends project beyond the periphery of the damper and are supported in said bearing means, whereby, as said frame is set transversely onto said flue, the damper enters through the cutout opening in the flue and said ends of the damper shaft means enter the opposed ends of said flue cutout opening, the ends of said inwardly projecting means on the frame forming obstructions to seating of the frame onto the flue excepting under force causing yielding inward distortion of the flue sheet metal for springback into interengagement with the projecting means upon the latter reaching respectively said spaced cutouts in the flue, and a cover-plate overlying said air-entry cutaway part of the frame and having means mounting it in adjustable position relative thereto to vary the size of the effective aperture for air passage.

11. A regulator for assembly to a sheet metal flue having an external surface that is convex and having a transverse cutout opening therein, said regulator comprising a saddle-like frame which is concave on its under side to receive therein and seat against the convex surface of the flue, said frame having bearing means in its opposed ends, a damper having shaft means respectively supported in said bearing means and having a greater area on one side of the axis of said shaft means than on the other for pivotal movement of the damper in one direction in response to pressure of flue gases, one of said shaft means projecting beyond the bearing means in one of said frame ends, the projecting end being round except for a relatively short terminal portion thereof that is conformed to provide two substantially flat converging side faces forming a pointing angle that is visible externally of the bearing means and whose bisector is in the plane of the damper, and a weighted lever arm having a hub that is slidable axially over said terminal portion that forms pointing angle and onto the round projecting end of said one shaft means to a position where said pointing angle terminal portion is visible at the outer end

of the hub, said hub being provided with means for securing it to said shaft end with said arm selectively positioned in rotational direction as is visibly determinable by reference to the pointing angle of said terminal shaft portion and thereby give the said weighted lever arm a predetermined angle to the plane of the damper according to the needed bias of the latter in opposition to the action of the flue gas pressure.

12. A regulator for assembly to a sheet metal flue having an external convex surface and having a transverse cutout opening therein, said regulator comprising a saddle-like frame which is concave on its under side to receive therein and seat against the convex surface of the flue, said frame having substantially self-cleaning bearing means in its opposed ends; a damper having shaft means respectively supported in said bearing means whereby, as said frame is set transversely onto said flue, the damper enters through the cutout opening in the flue and said shaft means enter the opposed ends of said cutout opening, each of said bearing means comprising a round hole in the end of the frame with its axis making a small angle to the axis of the damper shaft means and a sheet metal annulus of lesser outside diameter than said hole and an inside diameter greater than that of the shaft means for receiving the shaft means therein, said annulus having end flanges spaced apart by a distance greater than the thickness of the frame end, for freedom of rotary movement and of change of axial tilt of the annulus relative to the frame hole and relative to the shaft means as said damper and its shaft means oscillates and for thereby effect-shift and substantial expulsion of foreign matter such as soot from the bearing.

13. A regulator installation comprising a sheet metal flue that is of circular cross-section and recoverably deformable into substantially oval shape, said flue having a transverse cutout opening of an arcuate extent on the order of 180°, said regulator comprising a saddle-like frame which is concave on its under side to receive therein and seat against the convex surface of the flue, a damper on the concave side of said frame and pivotally supported in the opposed depending ends of said frame for entry through said cutout opening in the flue as the frame is set onto the latter, the depending ends of said frame each having a rigid extension integral therewith, said extensions being juxtaposed to each other on a chord of the concave curvature of the frame with the termini of said extensions spaced apart by a distance less than the diameter of the flue and thereby requiring deformation of the flue into substantially oval cross-section with its major axis at substantially right angles to said chord for continuation of movement of the frame in seating direction onto the flue, said flue having at its opposed sides portions which are located on a chord parallel to the minor axis of the deformed flue cross-section for respective accommodation of said juxtaposed frame extensions in response to completion of seating movement and for thereby permitting spring-back of the flue to circular cross-section with its convex surface engaged against the concave under side of the saddle-like frame.

14. A regulator as claimed in claim 13, in which said rigid extensions comprise each a lug formed integrally

with and out of the metal of the frame and projecting in substantially radial direction inwardly from the respective frame ends.

15. A regulator as claimed in claim 13, in which said frame is provided with means, operable subsequent to the snapback of the sheet metal of the flue, for securing the sheet metal of the flue against the under side of said frame adjacent said fixed projecting means and hold it against forcible distortion back into the aforesaid oval shape.
16. A regulator for assembly to a sheet metal flue of substantially circular cross-section and having a transverse cutout opening therein, said regulator comprising a saddle-like frame which is concave on its underside to receive therein and seat against the convex surface of the flue, a damper on the concave side of said frame and pivotally supported in the opposed dependent ends of said frame for entry through said cutout opening in the flue as the frame is set onto the latter, said frame having inwardly projecting rigid means carried by and movable with the frame and positioned on the said concave underside of the frame to provide a transverse spacing less than that provided by said concave underside of the frame, whereby to obstruct seating of said concave underside against said convex surface of the flue except upon distortion of the flue into substantially oval cross-section to lessen its transverse dimension for entry into said lesser transverse spacing and for subsequent snapback of the flue upon registry of the projecting means with appropriate aperture means in the sheet metal of the flue to interlock the latter and said frame and hold the frame seated against the convex surface of the flue, said inwardly projecting means having external surface configuration that provides freedom of movement therealong of the walls of said aperture means under the aforesaid snapback action of the flue.

17. A regulator as claimed in claim 13, provided with strap means extending from one end of said frame about the rest of the periphery of the flue to the other frame end for thereby confining the cross section of the flue against deformation back into substantially the aforesaid oval shape of cross-section.

18. A regulator as claimed in claim 17, in which the ends of said strap means are secured to the respective depending ends of the frame each by headed means with the headed ends thereof projecting radially inwardly from the concave surface of the frame and respectively forming the aforesaid rigid extension integral with said frame ends.
